UNITED STATES PATENT OFFICE

CHARLES K. DUNLAP, OF HARTSVILLE, SOUTH CAROLINA, ASSIGNOR TO SONOCO PRODUCTS COMPANY, OF HARTSVILLE, SOUTH CAROLINA, A CORPORATION OF SOUTH CAROLINA

DYEING APPARATUS

Application filed May 15, 1928. Serial No. 277,981.

The present invention relates to dyeing apparatus and particularly to apparatus designed and constructed for dyeing thread or yarn in the form of packages.

5 It is now becoming general practice to dye thread or yarn in the form of packages wound on perforated cores. The cores with their packages wound thereon are mounted on perforated dye liquor circulation pipes in 10 a dyeing vat. Dye liquor is forced through the perforations of the cores and through the packages, either inwardly or outwardly, by suction or pressure, or combinations of these. Then the drying and setting of the 15 dye is often accomplished by circulating hot or cold air therethrough in the same manner.

The circulation pipes pass through the cores, which are mounted thereon by supporting or securing means which also serve 20 to block the end openings against the passage of dye liquor, except, of course, the dye liquor which flows through the circulation pipe.

25 The object of the present invention is to provide an improved securing means whereby either a cylindrical or conical thread core may be supported upon a dye liquor circulation pipe. My improved supporting means is particularly useful when the cores are 30 fabricated of paper or other deformable material. Such tubes or cores are liable to be softened somewhat during the dyeing process, particularly when high temperatures of 35 dye liquor are employed. The ends of the cores tend to be stretched or deformed such as to bell out the material, especially under pressure, and permit leakage through the end openings of the core, thus decreasing the flow 40 through the thread. In this respect the leakage of the drying air is even greater than the leakage of the dye liquor.

45 However, by means of my improved thread core supporting devices, a paper or composition tube may be so mounted that it will at all times retain its proper relationship with the dye liquor circulation pipe and will not permit leakage around the ends of the tube.

50 Other objects and features of novelty will be apparent as the following description pro-

ceeds, when taken in connection with the accompanying drawings, in which:

Figure 1 is a longitudinal section of a dye liquor circulation pipe with its associated thread core mounted thereon according to one 55 form of the invention;

Figure 2 is a similar view showing another form of the invention for mounting a conical thread core; and

Figure 3 is a cross section taken along the 60 line 3—3 of Figure 2.

Referring more particularly to the drawings, the invention is illustrated in connection with a dye liquor circulation pipe 25, a portion of which is perforated as shown to 65 permit the circulation of dye liquor therethrough. The pipe 25 served to support a perforated thread core 26, upon which a thread package 27 has been wound prior to 70 the dyeing operation.

The dye liquor circulation pipe 25 is connected in any desired manner to a main supply conduit 20, so as to communicate therewith, and as shown in Fig. 1, a hollow threaded plug 31 is mounted in an aperture 75 32 in the main supply conduit 20 and the pipe 25 is brazed or otherwise secured inside the plug 31 in such a manner that a smooth bore is produced. The outer end of the pipe 25 is threaded and closed as at 33.

To mount the perforated thread cores 26 on the pipe 25, ferrules 34 and 35 are provided. Each of these ferrules is provided with an axial boss 37 which is substantially cylindrical and of such diameter as to closely fit the end of the core 26 when the core is placed thereover. Each of the ferrules is also provided with a radial shoulder 38, which abuts the end of the core 26, and the boss and the shoulder form a seat for the end of the core. However, in the preferred form of the invention an annular flange 39 is provided, which is substantially cylindrical and provided with an inner diameter such as to snugly fit the outside surface of the core 26. With 95 this arrangement, the boss, shoulder and flange form a groove which receives the end of the core to give it very firm support.

The ferrule 34 is preferably fixed on the pipe 25 in the position shown so as to be sub- 100

stantially integral with the pipe 25 and the plug 31. The ferrule 35, however, is removable to permit the core and package to slide over the outer end of the tube. It is desirable to provide the outer ferrule 35 with means for urging it against the end of the core 26, to put the core under slight compression so that its ends are snugly received by both ferrules, preventing leakage around the ends of the cores. In the form shown the plug 33 is threaded as at 40 and the ferrule 35 is tapped as at 41. It should be noted that the boss 37 is substantially cylindrical and has no tendency to rupture the core, and that the annular flange 28 serves to confine the outer surface of the core. With this arrangement the core may be compressed without exerting any radial force tending to rupture the thread core.

Furthermore, it should be noted that the ferrule 35 is solid, being drilled only part of the way through, where it is tapped to receive the plug 33. Hence, even though the threads 40 and 41 do not themselves form a tight joint, no leakage will occur at this point.

The mounting above described is peculiarly suitable for thread packages having cylindrical cores, but it is equally within the purview of my invention to provide a mounting for thread packages having conical cores. The arrangement for this purpose is shown in Figures 2 and 3. In these figures, the conduit 20, plug 31, threads 32, perforated pipe 25 and outer plug 33 are identical with those previously described.

In order to mount conical perforated thread cores such as indicated at 45, a modified ferrule 46 is provided. The ferrule 46 may be mounted on the pipe 25 in any desired manner, but in the preferred form shown it is integral with the plug 31 and the pipe 25. The ferrule 46 is of a diameter somewhat greater than the base of the core 45, and is provided with an axial boss 47 which snugly receives the inner surface of the base of the core 45, the end of which abuts against a radial shoulder 48. An annular flange 49 confines the outer edge of the base of the core, so that the abutment 47, the shoulder 48 and the flange 49 define a groove in which the base of the core is seated. The outer or smaller end of the core 45 is supported by a ferrule 50 which is somewhat similar to the ferrule 35 shown in Figure 2. The ferrule 50 is solid, being drilled only partially through where it is tapped to receive the plug 33. This ferrule has an axial boss 51 which receives the inner surface of the small end of the core 45, as well as a radial shoulder 52 and an annular flange 53. It will be readily apparent that the ferrules 46 and 50 serve to support the conical thread core 45 in the same manner that the ferrules 34 and 35 support the cylindrical thread core 26.

While two embodiments of the invention have been shown and described in great detail for the purposes of full and complete disclosure, the breadth of the invention is not limited by any of the details shown, but includes such embodiments of the broad idea as come within the scope of the following claims.

Having thus described the invention, what is claimed as new and desired to be secured by Letters Patent is:

1. In a dyeing apparatus, in combination, a fluid conduit, an elongated spindle-like member projecting therefrom, the outer end of which is threaded, a tubular perforated open-ended and relatively thin-walled fiber thread core encircling said member and having its inner wall spaced therefrom, said member having an aperture formed therein through which fluid may pass from said conduit into the space between the exterior surface of the member and the thread core, or in the reverse direction, and means for supporting the thread core and sealing the ends of the same against the passage of fluid, said means comprising two spaced elements supported upon the elongated member, one element being imperforate and having threaded engagement with the outer end of said member and the second element encircling the said member at a point between the outer element and conduit and making a fluid tight joint with the member, said elements having mutually facing annular grooves within which the ends of said core project, the diameters of the inner and outer walls of each groove being substantially the same as the diameters of the inner and outer walls of the adjacent ends of the core, respectively, the ends of the core being firmly supported at all times against radial distortion in both directions, due to fluid pressure, by the walls of the grooves, and the ends of the core being seated on the bottoms of the grooves, whereby the core is so supported that all fluid passing through said aperture in a dyeing or drying process is caused to flow through the perforations in the core, none flowing through the ends thereof even though the core may be softened as the result of the action of the treatment fluid thereon.

2. In a dyeing apparatus, in combination, a fluid conduit, an elongated spindle-like member projecting therefrom, a tubular perforated open-ended and relatively thin-walled fiber thread core encircling said member and having its inner wall spaced therefrom, said member having an aperture formed therein through which fluid may pass from said conduit into the space between the exterior surface of the member and the inner wall of the encircling thread core, or in the reverse direction, and means for supporting the thread core and sealing the ends of the same against the passage of fluid, said means comprising

- two spaced elements supported upon the elongated member, one element being adjustably detachably secured to the outer end of said member and the second element encircling the said member at a point between the outer element and conduit and making a fluid tight joint with the member, said elements having mutually facing annular grooves within which the ends of said core project,
5   the inner walls of said grooves being closely juxtaposed to the inner wall of the core, and the outer walls of the grooves being closely juxtaposed to the outer wall of the core, the ends of the core being seated on the bottoms
10   of the grooves, whereby the ends of the core are supported at all times against radial distortion in both directions due to fluid pressure and substantially all of the fluid passing through said aperture in a dyeing or drying
15   process caused to flow through the perforations in the core, and the core ends are maintained intact despite possible softening of the fiber of the core.
20
25   In testimony whereof I hereunto affix my signature.

CHARLES K. DUNLAP.
